METHOD FOR INCREASING THE PRODUCTION OF OIL-WELLS.

1,190,268.

Specification of Letters Patent.

Patented July 11, 1916.

Application filed January 20, 1914. Serial No. 813,159.

To all whom it may concern:

Be it known that I, IRWIN L. DUNN, a citizen of the United States, residing at Marietta, Washington county, Ohio, have invented certain new and useful Improvements in Methods for Increasing the Production of Oil-Wells, of which the following is a specification.

The history of practically all oil wells which, when opened at first deliver the oil above the surface of the ground without mechanical or other assistance, is that the flow gradually or rapidly decreases with the lapse of time until ultimately it becomes insignificant or ceases altogether. It has long been the practice when the flow becomes too small to torpedo the well which consists in exploding a charge of dynamite or other high explosive at the bottom of the well, or where the well traverses the oil rock, the precise action of which on the rock is perhaps not fully understood though the result is ordinarily to increase the flow. The beneficial effect, however, is of comparatively short duration and the next step ordinarily is to raise the oil by means of a mechanical pump inserted in the well. It is probable, if not demonstrable, that the reason for the diminution in the flow of oil is not entirely, if at all, the depletion or exhaustion of the supply of oil, but rather that the pressure of natural gas which is found in such wells becomes lowered to a point where it is ineffective, if not to atmospheric pressure. It is apparently a usual feature of oil bearing sand or rock bodies that they are each inclosed or surrounded by an impervious or substantially impervious rock forming a dome or cavity which is sealed above the oil rock. Natural gas, which usually accompanies oil and is probably given off by the materials from which petroleum is formed, rises by reason of gravity to the upper portion or layers of the porous oil sand or rock where it is imprisoned within the cavity and exerts a great pressure on the oil. When, therefore, the oil rock is tapped by a well the natural gas escapes in great volumes through the latter together with more or less of the oil so that the pressure is diminished as referred to above. It has been proposed heretofore and actually practised, to imitate or substitute for the effect of the natural gas pressure in such wells a pres-

sure of atmospheric air or other gas until the pressure upon the oil sand is sufficiently restored to again have an effective action in driving the oil from the rock. Ordinarily, the action of this air pressure is used only to drive the oil from the surrounding rock to the bottom of the well or wells from which it is raised by pumping though of course by supplying sufficient air under pressure it may be further utilized to raise or assist in raising the oil in the well. In the usual practice of this process air under pressure is supplied to one or more of a group of oil wells, those to which the pressure is not applied being utilized for receiving and pumping off the oil. The air forced in finds its way to the upper part of the oil sand or rock and it exerts its pressure in much the same way as the natural gas originally found associated with the oil, and travels, probably mainly through the upper layers of the oil rock, from the inlet well to the wells which are being pumped, taking or driving more or less of the oil held in the pervious rock with it. It is found that the air supplied to the rock will penetrate to great distances from the entering well and increase the productions of wells for a considerable distance around the inlet well. An objection to this method of increasing the production of oil wells as at present practised is that it is not sufficiently economical because its action is not restricted to the particular territory and group of wells held by the party operating the process, but on the contrary the air escapes to other wells in the surrounding territory, which of course exhausts and consumes the artificially applied pressure at the expense of the operator supplying the same for the benefit of his own wells, and also causes a loss of oil by him.

It is the purpose of the present invention to largely obviate this difficulty by exerting a directive action upon the supplied air or gas and the oil released thereby so that the beneficial effect of the process is to a large extent confined to the wells of the operator of the process and is not wasted upon remote territory or wells upon adjacent leases of property.

In the accompanying drawing, I having illustrated in a diagrammatic way a suitable form of apparatus for practising my

110

process, though it is to be understood that the specific form of apparatus is immaterial so long as the process as set forth in the following claims is employed. The specific disclosure both of process and apparatus is for the purpose of exemplification only, the scope of the invention being set forth in the following claims in which I have endeavored to distinguish it from the prior art so far as known to me without, however, relinquishing or abandoning any portion thereof.

10 The drawing represents a vertical section on a plane through a pair of wells which are more or less remotely located with respect to each other.

15 In the well A, which represents one of a group, is inserted the usual pump B and from the upper portion of the casing C of the well a pipe D leads to an air or gas suction pump E which may be of any desired type.

20 G represents a well preferably of the same group and suitably located with respect to the well A, and without any oil pump but connected by a pipe H with a compressor J by which air may be supplied thereto under the desired pressure. Preferably upward of 40 pounds pressure is supplied to the well 25 G by the compressor J as in the process heretofore used. The air entering the oil rock tends to disperse in all directions carrying the oil with it and flow in whichever directions areas of least pressure exist. By 30 the operation of the suction pump E referred to above, the pressure in the wells to which it is connected and in the rock surrounding the same, is reduced below the

normal. This region therefore has a marked tendency to draw to it the air supplied to the well G and with it the petroleum displaced thereby from the surrounding rock, which finds its way to the well from which it is pumped. By thus supplementing the forcing of the air at the inlet well with suction at the wells to which it is desired to drive it, a directive effect is had upon the air and oil which causes them to flow to the desired wells where the oil may be pumped in the usual way. It is found advantageous to provide a number of wells connected to suction along the boundaries of the territory being worked and especially between the pressure well and wells in adjoining territories to secure the full benefit of the operation of the process.

50 I claim:

1. A process for increasing the production of oil wells consisting in forcing a gas into one of the wells of a group under pressure, exhausting gas from other wells and pumping oil from the latter.

2. A process for increasing the production of oil wells consisting in forcing gas into one of the wells of a group under pressure and exhausting gas from other wells of the group thereby causing the oil to flow from the direction of the first said well toward the wells from which the gas is being exhausted and then mechanically pumping oil from the latter said wells.
